DESIGN FOR A TEXTILE FABRIC FOR UPHOLSTERY

Edna F. Leonhardt, Mount Airy, Philadelphia,
Pa., assignor to Northampton Textile Company, Mount Holly, N. J., a corporation of New Jersey

Application November 2, 1937, Serial No. 72,593

Term of patent 3½ years

To all whom it may concern:

Be it known that I, Edna F. Leonhardt, a citizen of the United States, residing at Mount Airy, Philadelphia, in the county of Philadelphia, and State of Pennsylvania, have invented a new, original, and ornamental Design for a Textile Fabric for Upholstery, of which the following is a specification, reference being had to the accompanying drawing, forming part thereof.

The figure is a face view of a textile fabric for upholstery embodying my design, a unit of the design being indicated by broken boundary lines.

The dominant features of the design consist of a central cluster a with surrounding leaves b having the distinctive medial lines c.

I claim:

The ornamental design for a textile fabric for upholstery, as shown and described.

EDNA F. LEONHARDT.
